(57) **CLAIM**

The ornamental design for a liquid crystal polarizer for a device for measuring fluorescence polarization, as shown and described.

DESCRIPTION

FIG. 1 is a front elevational view of a liquid crystal polarizer for a device for measuring fluorescence polarization, showing our design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top and left front perspective view thereof; and,

FIG. 8 is a bottom and right rear perspective view thereof.

The broken line showing is for illustrative purposes only and forms no part of the claimed design.
